UNITED STATES PATENT OFFICE.

ÁRMIN TETÉLENI, OF BUDAPEST, HUNGARY.

HAND PRESS.

Application filed March 13, 1925. Serial No. 15,300.

To all whom it may concern:

Be it known that I, ÁRMIN TETÉLENI, a Hungarian subject, residing at 10 Jozsef Ter, Budapest V, Hungary, have invented 5 certain new and useful Improvements in or Relating to Hand Presses, of which the following is a specification.

The present invention relates to a hand press for the manufacture of rectangular 10 bodies particularly building elements.

According to one feature of the invention a cover plate is mounted opposite the press plunger for the preliminary compression of the material and is made movable for this 15 purpose.

According to another feature of the invention the press plunger itself is provided with two transmitting devices, one of which serves for pressing and the other for expelling the finished bricks.

Finally a cam used in the press according to the invention is specially shaped whereby the hardening thereof is facilitated.

An example of a constructional form of 25 the invention is illustrated in the accompanying drawings, in which:

Figure 1 is a transverse section of a brick press according to this invention;

Figure 2 is a longitudinal section thereof; 30 Figure 3 illustrates a special constructional form of the cam in section, and

Figure 4 shows the cam in front elevation.

On the standards of the machine 1 is mounted a mould 2 the hollow space of 35 which is bounded below by a press plunger 3 and above by a cover plate 4 which is connected to levers 7 fulcrumed on pivots 5 and 6. The levers 7 are prolonged into rods 8 which may be provided with a handle 9 passing through their ends and arranged longitudinally of the machine. The pivots 5 and 40 6 pass through yokes or stirrups 10, 11 which are engaged over a lower transverse support 12. The yoke or stirrup 10 is also screwed 45 to the transverse support while the yoke or stirrup 11 can be disengaged, so that the lever 7 can be rocked by the aid of the handle 9 into the position indicated by the dotted lines.

The press plunger 3 carries on its lower 50 part a roller 14 which rotates on a spindle 13 and bears upon a motion transmitting device 16 which latter is keyed on a shaft 15 carried in the transverse support 12. As a 55 transmitting device it is most convenient to use a power cam. On the end of the shaft

15 is keyed a hand lever 17 which serves to operate the transmitting device.

The press plunger 3 is provided with a lower extension 18 to which is attached a 60 pedal 20 rocking on the spindle 19. By operating this pedal the plunger 3 is raised until its thrust plate reaches the same level as the upper limit of the hollow space of the 65 mould 2.

The press works in the following manner: The yoke or stirrup 11 is disengaged from the transverse support 12 and the lever 7 is swung over together with the cover plate 4 into the position indicated by dotted lines. 70 Simultaneously the yoke or stirrup 11 is swung together with the arms whereby the hollow space of the mould 2 is exposed or uncovered at the top. The hollow space is 75 then filled with the material to be pressed and the arm 8 pressed downwards by means of the handle 9, the cover plate 4 imparting the necessary preliminary compression to the material. To enable the measure or amount 80 of this preliminary compression to be regulated as may be desired the moulds 2 are stocked in different heights.

When the cover plate has reached its lowest position, the yoke or stirrup 11 is engaged over the transverse support 12 and the lever 17 is then depressed in the direction indicated by the arrow *a*. The cam 16 thus rotates and lifts the press plunger by means of the roller 14 whereby the pressing 85 of the moulded article or object is completed. After the lever has been brought back to its original position the yoke or stirrup 11 is 90 disengaged from the transverse support 12 and the cover plate swung into the position indicated by dotted lines by means of the rod 8. The pedal 20 is then operated whereupon its other end imparts a further upward movement to the press plunger 3 so that the plunger lifts the completed brick out of the mould after which the brick can be removed. 95 During this movement the roller 14 naturally moves away from the cam 16 but drops back on to it again when the pedal is released. The mould is now refilled and the moulding operation repeated.

The power transmitting cams used here have hitherto been constructed substantially in the form of general cylindrical surfaces, the fundamental curve of which (i. e. the directrix) was constituted by the power transmitting curve itself. The hardening of 100 such cams has given rise to much waste owing

ing to the unequal distribution of the masses in the cams.

In the course of the experiments which have been made with various forms of cams it has been unexpectedly found that the hardening of these cams can be effected quite easily and almost without any waste if the cam be provided with a hub round the hole in the centre.

10 In Figures 3 and 4 of the drawing the cam is denoted by 21 and the hub portion according to this invention by 22. This construction also offers the additional advantage that a longer key can be used when fixing the 15 cam on the shaft and the hub portion also lessens the bending strains on the shaft by better distribution of pressure.

It has been found to be most advantageous if the full axial length of the cam 20 so constructed be made to lie between the greatest diameter of the cam and one and a half times this diameter.

What I claim and desire to secure by Letters Patent of the United States is:—

25 1. A hand press for the manufacture of rectangular bodies particularly building elements, comprising a cover plate pivotally mounted with respect to the press plunger and producing a preliminary compression of 30 the material to be pressed, and a locking device comprising a yoke on said plate adapted to be engaged over a lower transverse support of the press.

35 2. A hand press for the manufacture of rectangular bodies particularly building elements, comprising a cover plate pivotally mounted with respect to the press plunger and producing a preliminary compression 40 of the material, a locking device comprising a yoke on said cover plate adapted to be engaged over a lower transverse support of the press, and a motion transmitting device indirectly connected to the press plunger.

45 3. A hand press for the manufacture of rectangular bodies particularly building elements, comprising a cover plate pivotally mounted with respect to the press plunger and producing a preliminary compression of 50 the material to be pressed, a yoke on said

plate adapted to be engaged over a lower 50 transverse support of the press to act as a locking device, a motion transmitting device comprising a power cam and a secondary transmission by means of which the plunger can be lifted off the cam. 55

4. A hand press for the manufacture of rectangular bodies particularly building elements, comprising a cover plate pivotally mounted with respect to the press plunger and producing a preliminary compression of 60 the material to be pressed, and a yoke on said plate adapted to be engaged over a lower transverse support of the press to act as a locking device, a motion transmitting power cam, a secondary transmission by 65 means of which the plunger can be lifted off the cam, and interchangeable moulds of different heights adapted to be inserted in the press to serve for the regulation of the degree of preliminary compression. 70

5. A hand press for the manufacture of rectangular bodies particularly building elements, comprising a cover plate pivotally mounted with respect to the press plunger and producing a preliminary compression of 75 the material to be pressed, a yoke on said plate adapted to be engaged over a lower transverse support of the press to act as a locking device, a motion transmitting power cam provided on both sides with a hub and a 80 secondary transmission by means of which the plunger can be lifted off the cam.

6. A hand press for the manufacture of rectangular bodies particularly building elements, comprising a cover plate pivotally 85 mounted with respect to the press plunger and producing a preliminary compression of the material to be pressed, a yoke on said plate adapted to be engaged over a lower transverse support of the press to act as a 90 locking device, a motion transmitting power cam provided on both sides with a hub the axial length of which is not less than the greater diameter of the cam and not greater than one and a half times this diameter and 95 a secondary transmission by means of which the plunger can be lifted off the cam.
